UNITED STATES PATENT OFFICE

GUSTAFF F. HEISS, OF EVERETT, WASHINGTON.

COPY-HOLDER.

SPECIFICATION forming part of Letters Patent No. 657,599, dated September 11, 1900.

Application filed April 2, 1900. Serial No. 11,179. (No model.)

To all whom it may concern:

Be it known that I, GUSTAFF F. HEISS, a citizen of the United States, residing at Everett, in the county of Snohomish and State of Washington, have invented certain new and useful Improvements in Copy-Holders, of which the following is a specification.

My invention pertains to improvements in copy-holders, the construction and advantages of which will be hereinafter set forth, reference being had to the accompanying drawings, in which—

Figure 1 is a perspective view of the apparatus viewed from one side; and Fig. 2, a similar view, the device being seen from the front.

The object of my invention is to provide a simple and efficient copy-holder wherein the indicator or line-marker may be moved step by step or line by line down the face or edge 20 of the sheet to indicate a particular point or line on the page.

Referring to said drawings, A denotes the base of the apparatus, which is preferably in the form of a box containing a drawer B for the reception of the copy or other material used in connection with the device. Hinged to the front portion of the base or box is a support C, preferably formed with a series of cross-notches D in its rear face, said notches 30 working in conjunction with a brace E, the lower end of which bears in a notch formed in the rear face of the box. The inclination of the support C may be varied by placing the upper end of the brace E in one or another of said cross-notches D, as will readily be understood.

Suitable guide rods or wires F are secured between the upper end of the support C at one side thereof and a projection G, formed 40 at the lower end of said support C. These wires or rods serve as guides for a movable index-finger or pointer H, between which the wires or bars pass, as will be noted upon reference to Fig. 1.

To normally maintain the index-finger or pointer H in its elevated position, I employ a spring I. (Best seen in Fig. 1.) Said spring, as will be noted, is bent at right angles at one end and secured at the rear of the box or base

50 A at the farther side thereof, while the opposite end extends upwardly and is connected to the index-finger or member H. This con-

nnection is made by simply bending the end of the spring and passing it through a hole or opening formed in said index-finger H. 55 Normally this spring serves to hold the index-finger or pointer in its elevated position, and to provide for the step-by-step movement of the pointer downward along the edge of the sheet to indicate the various lines a simple device is employed, which will now be described.

Secured upon the side of the base or box A, near the front end thereof, is a plate J, carrying a grooved wheel or pulley K, to the 65 axle of which is secured a toothed or ratchet wheel L, the pulley and wheel rotating as one. Extending from the pulley and made fast thereto is a cord or band M, the opposite end of which is secured to the index-finger or 70 pointer H in any suitable manner.

To actuate the pulley and ratchet-wheel, I employ a key N, which is connected to one end of a spring bar or lever O, said lever being fulcrumed at a point upon the plate J in 75 rear of the pulley and ratchet-wheel. A pin P is placed beneath the lever intermediate its fulcrum and the ratchet-wheel, which pin normally holds the actuating tooth or lug Q, carried by the lever, from engaging the teeth 8c of the ratchet-wheel. The normal position of this lever and its tooth is shown in Fig. 1, and it will be seen that upon depressing the key the lever will be forced down and the tooth or lug Q will engage the ratchet-wheel 85 and advance the same one step, thereby winding up the cord or band, and drawing the indicating or index finger down one line. To prevent the band or cord from unwinding around the pulley, a second lever R is mounted in a manner similar to the lever O above referred to, except that said second lever occupies a position below the ratchet-wheel and its tooth or pawl S normally engages the teeth 90 of the wheel and prevents any backward or 95 retrograde movement, thereby holding the pulley and band, and consequently the index-finger or pointer, in the position to which it has been drawn by the depression of the key N.

A pin T is placed beneath said spring arm or lever R and holds the same so that the tooth or pawl S will be normally in engagement with the teeth of the ratchet-wheel. A finger-key U is secured upon the outer end

of the lever R in order that it may be readily actuated when it is desired to release the ratchet and that the spring may be free to draw the index-finger or pointer H up to its highest position. This of course will take place after the index-finger or pointer has traversed the length of the sheet and a new sheet has been placed in position. The sheet or copy is denoted by the reference-letter V 10 in Fig. 2. As the index-finger or pointer is drawn down the spring I will of course move backward slightly, and it is for this reason that it is connected to the box in the manner shown and described—that is, to permit such 15 rearward movement.

By removing the brace E the support C may be folded down upon the box, the device being thus made compact and occupying but a comparatively-small space, while 20 the brace may be placed in the drawer for safe keeping.

Having thus described my invention, what I claim is—

1. In a copy-holder, the combination of a 25 suitable base; a copy-support extending up therefrom; an index-finger adapted to move over said support; a spring for normally holding said index-finger in its elevated position; and means for drawing said index-finger downwardly step by step against the spring, substantially as described.
2. In a copy-holder, the combination of a 30 suitable base; a copy-support extending upward therefrom; an index-finger or pointer mounted at one side of said support; a spring for normally holding said index-finger or pointer in its elevated position; means for drawing said index-finger downwardly against the action of the spring; and mechanism for actuating said means step by step, substantially as described, whereby the index-finger or pointer will be drawn down one space at a time.
3. In a copy-holder, the combination with a 35 suitable base, of a copy-support extending upward therefrom; suitable guides connected to one side of said support; an index-finger mounted and movable upon said guides; a spring for normally holding said index-finger 40 in its elevated position; and means for drawing said finger downwardly step by step against the action of the spring.
4. In a copy-holder, the combination of a 45 suitable base; a copy-support hinged to the forward end thereof; an adjustable brace for maintaining said support in position; guides secured to the side of said support; an index-finger mounted and movable upon said guides; a spring for maintaining said finger 50 in its elevated position; a band or cord secured to said index-finger; a pulley journaled upon the side of the base; and means for moving said pulley step by step and winding

the cord thereon, substantially as described, whereby the index-finger will be moved downwardly against the action of the spring. 65

5. In a copy-holder, the combination of a suitable base; a copy-support hinged to the forward end thereof; an adjustable brace for maintaining said support in any desired position; guides connected to the side of said support; an index-finger or pointer mounted and movable upon said guides; a spring for maintaining said index-finger in its elevated position; a pulley journaled upon one side of the 70 base; a cord or band connecting said index-finger and the pulley; a ratchet-wheel connected to the pulley; and means for moving said ratchet-wheel step by step and thereby winding up the cord and drawing down the 75 index-finger. 80

6. In a copy-holder, the combination of a suitable base; a copy-support hinged to the forward end thereof; means for holding said support in any desired position; guides connected to one side of said support; an index-finger or pointer mounted and movable upon said guides; a spring for maintaining said index-finger or pointer in its elevated position; a pulley journaled upon one side of the base; 90 a ratchet-wheel connected to said pulley; a band or cord extending from the index-finger or pointer to said pulley; and a spring arm or lever provided with an operating-key adapted to actuate the ratchet-wheel, and thereby wind the cord or band about the 95 pulley.

7. In a copy-holder, the combination of a suitable base; a copy-support hinged to the forward end thereof; means for maintaining 100 said support in position; guides secured to one side of said support; an index-finger or pointer mounted and movable upon said guides; a spring for maintaining said index-finger in its elevated position; a pulley journaled upon one side of said base; a band or cord extending from the index-finger to said 105 pulley; a ratchet-wheel connected to said pulley; a lever O fulcrumed at a point in rear of said ratchet-wheel and provided with an actuating tooth or pawl Q; means for normally holding said tooth out of contact with the ratchet-wheel; a second lever R also fulcrumed in rear of the ratchet-wheel and provided with a pawl S adapted to engage the 110 teeth of the ratchet; and means for normally holding said pawl in engagement with the ratchet-wheel, substantially as and for the purpose described. 115

In testimony whereof I have signed my 120 name to this specification in the presence of two subscribing witnesses.
